DESIGN FOR A GIFT BAG

Jean E. Vivaudou, New York, N. Y.

Application May 20, 1948, Serial No. 146,478

Term of patent 3½ years

(Cl. D58—2)

To all whom it may concern:

Be it known that I, Jean E. Vivaudou, a citizen of the United States, residing at New York, in the county of New York and State of New York, have invented a new, original, and ornamental Design for a Gift Bag, of which the following is a specification, reference being had to the accompanying drawing, forming a part thereof.

In the drawing:

Fig. 1 is a front perspective view of a gift bag, showing my new design; and

Fig. 2 is a rear elevational view of the same.

I claim:

The ornamental design for a gift bag, as shown.

JEAN E. VIVAUDOU.
